CLAIM

The ornamental design for a dual spray dispenser, as shown and described.

DESCRIPTION

The present application is related to U.S. patent application Ser. No. 15/132,025, filed Apr. 18, 2016 which is now granted U.S. Pat. No. 9,931,656 and entitled “Dual Chamber Spray Dispenser”, and U.S. patent application Ser. No. 14/683,232, filed Apr. 10, 2015 which is now granted U.S. Pat. No. 9,610,598 and entitled “Trigger-Dispensing Device for Two or More Liquids”. The disclosure of each of the above patent applications is incorporated by reference in its entirety.

FIG. 1 is a top perspective view of a dual spray dispenser. FIG. 2 is a bottom perspective view of the dual spray dispenser shown in FIG. 1.

FIG. 3 is a first side view of the dual spray dispenser shown in FIG. 1.

FIG. 4 is a second, opposite side view of the dual spray dispenser shown in FIG. 1.

FIG. 5 is a rear view of the dual spray dispenser shown in FIG. 1.

FIG. 6 is a front view of the dual spray dispenser shown in FIG. 1.

FIG. 7 is a top plan view of the dual spray dispenser shown in FIG. 1; and,

FIG. 8 is a bottom plan view of the dual spray dispenser shown in FIG. 1.

(Continued)

Any broken lines in the Figures depict portions of the dual spray dispenser that are not part of the claimed design.
